UNITED STATES PATENT OFFICE.

FERDINAND GUNDORPH, OF SAN FRANCISCO, CALIFORNIA.

GYRATING-PENDULUM ESCAPEMENT.

SPECIFICATION forming part of Letters Patent No. 626,807, dated June 13, 1899.

Application filed September 21, 1898. Serial No. 891,503. (No model.)

To all whom it may concern:

Be it known that I, FERDINAND GUNDORPH, a citizen of the United States of America, residing in the city and county of San Francisco and State of California, have invented certain new and useful Improvements in Gyrating Pendulum Escapements, of which the following is a specification.

My invention relates to an improved pendulum-escapement to govern chronometrically a clock-movement or other similar mechanism; and the same consists in certain novel parts and combination of parts, as hereinafter explained and pointed out, producing an improved governing mechanism in which the pendulum is impelled continuously in one direction and is detached or disconnected from the power in such manner as not to be affected in its motion by any irregularity in the motive power or force.

The novel features of this improvement include a pendulum having a gyrating movement without points of rest and an escapement by which the motive power is applied 25 to the pendulum without being directly connected to it.

The following description explains at length the nature of my said improvements and the manner in which I proceed to construct, apply, and carry out the same, reference being had to the accompanying drawings, forming part of this specification, in which—

Figure 1 represents in side elevation a pendulum-escapement for clocks embodying my invention. Fig. 2 is a front view taken from the left-hand side of Fig. 1. Fig. 3 is an inverted plan of the upper part of the mechanism with the pendulum-rod cut off at xx , Fig. 1. Fig. 4 illustrates the position of the parts at one point in the movement of the pendulum. Figs. 5 and 6 are details of the oscillating lever that gives motion to the pendulum and the spindle connecting the lever with the power-pinion. Fig. 7 illustrates a construction of weight and carrier in which two balls are employed in place of a single ball.

A indicates a bracket fixed to a stationary support X and standing out from that support in a horizontal plane.

A' is an arm beneath the bracket A, to the under side of which it is secured by screws a' . On this bracket is mounted a pinion P, to

which the motive force or power is applied. From the under side of the same piece is suspended the pivot on which the pendulum 55 swings.

C is the pendulum-rod, and C' the weight or bob on the lower end.

D is a head or fitting on the upper end of rod C, having a broad top flange with a segmental recess or opening d' , into which the end of the arm A' extends from one side. C² is a conical pin fixed in the end of that arm and having its point coinciding with the longitudinal center line of the pendulum-rod. 65

B is a disk or circular plate fixed on the top of the head D by screws b' in such position that the center of the disk is coincident with the longitudinal axis of the pendulum-rod and the top face of the disk is at right angles to that axis. A jeweled bearing b^2 for the point of the pin C² is fixed in the center of the disk B, and the recess in the fitting D is of proper dimensions to admit the arm A' and allow clearance for the pendulum to swing 70

without striking the arm. On this pivot the disk B thus mounted is free to tilt or move in any direction out of a horizontal position under any disturbing force that is sufficient to throw the pendulum beyond the center of 75 gravity.

E is a spindle or arbor supported in upright position in bearings a^5 a^6 to rotate directly over and in line with the center on which the pendulum is suspended. The pinion P, fast 85 on this spindle, forms the medium through which in turn the governing force of the pendulum is applied. On the lower end of this spindle is fixed a sleeve F, having on the lower end a fork F', between the arms of which a 90 rod G is pivoted to oscillate freely in a vertical arc. H is a weight on one arm or member of this rod, and K is a counterweight on the opposite arm. This rod, forming the carrier of the weight H, is loosely hung on the center 95 F', so that the weight rests at all times upon the disk B, and through the force of gravitation acting on its mass the weight will tilt the disk out of a horizontal plane, as illustrated in Fig. 4, thereby throwing the pendulum beyond the center of gravity. The amount or degree of this deflection is determined and regulated both by the mass of the weight H and its distance radially from the center of 100

oscillation of the carrier. By the revolutions of this carrier around the center F' under the motive force applied to the spindle the weight H travels around the surface of the disk in a circular path, and the resultant movement of the lower end of the pendulum-rod is a continuous circular one. The weight H is best formed of a spherical ball loosely mounted on the carrier G, so as to rotate freely by frictional contact with the surface of the disk. In the slight modification represented in Fig. 7 two balls are mounted to rotate freely on pins or axles in place of a single ball. This construction has the advantage of producing bearings for the balls with a small amount of frictional surface. The counterweight K employed to regulate the amount or degree of pressure of the ball H and the consequent deflection of the disk is movable on the carrier G and is fixed at the required point beyond the pivot by a set-screw k'.

L L' are stop-pins fixed in the plate A, from the under side of which they project or extend downward at points equidistant from the center and from one another around a circle that is concentric with the disk B of the pendulum and in the circular path described by the end of the rod or carrier G when that part stands horizontally. When thus placed, the stop-pins intercept and arrest the movement of the rod in its revolutions about the center and they are made of such length that in the horizontal position of the disk B the outer end of the rod lies against the pin, and in the movement of that end in a circle, as produced by the motive force, the rod is arrested momentarily until the angular deflection of the disk B under the force of gravitation acting upon the weight H allows the end of the rod to slip off and pass under the point of the stop-pin. In this manner the weight released at each stop-pin is caused to move forward at definite points in the circle, which points are controlled and regulated by the movement of the disk. The stop-pins are adjustable perpendicularly in the plate for the purpose of regulating their length or the amount of their projection below the line of the weight-carrying rod when that part stands horizontally.

As thus constructed and combined for operation the pendulum is moved and caused to swing entirely by the force of gravitation acting upon the weight traveling on the disk, and a uniform movement of the pendulum is produced and maintained irrespective of any irregularity in the motive force. Any variation in such force or power, while it may cause the weight to travel on the disk from one stop-pin to the next with greater or less irregularity of motion, will simply cause the weight-carrier to strike the stop-pin with greater or less force without disturbing or affecting the regular movement of the pendulum. This movement of the pendulum also when it is started in its gyrations is a continuous one, without points of rest or cul-

minating points, as in the case of all pendulums that have a simple oscillating movement, and by virtue of this peculiar gyrating motion maintained without being directly connected to or with the motive force the pendulum absolutely determines the moment of escape of the weight at each stop-pin, and thus accurately controls and regulates the intervals of rest or momentary stops in the forward motion of the weight-carrier. These jumps or intervals will be indicated by the seconds-hand, with which the pinion P would be connected in the clock-movement, and the number of such impulses required to cause the hand to stop momentarily at given points on the dial to indicate the divisions of a second are regulated by the number of stop-pins L employed. These in any case cannot be less than three, as that number is required to produce the movement of the pendulum-weight in a true circle around the point of suspension.

A spiral spring S, connected at one end to the pendulum-rod by a collar S' and at the other end to a fixed point above, such as to the support A', acts to hold the disk B in position with relation to the support on which it is suspended and without interfering with or disturbing the continuous movement of the pendulum in a true circle, thus keeping the pendulum on the part D from making contact with the support A' while in motion.

Having thus fully described my invention, what I claim as new therein, and desire to secure by Letters Patent, is—

1. In a gravity-escapement the combination, with the power shaft or spindle, of a disk balanced and free to move on a central pivot, having its center of gravity located at a distance below the pivot; an oscillating carrier connected with the power-shaft to travel in a circle under the rotation of said shaft and having movement in a vertical arc; a weight on the said carrier adapted to travel on the surface of the disk; and stop-pins located at intervals of distance apart in a circle and in the path of the weight-carrier in its revolution.

2. In a gravity-escapement, a balanced disk pivotally mounted to move in any direction out of a horizontal plane and having its center of gravity located below its supporting-pivot; an oscillating carrier capable of traveling in a circle over the said disk; a weight on said carrier adapted to make contact with the surface of the disk and by the force of gravitation to deflect the disk; a counterweight on the carrier; and the stop-pins as a means of intermittently arresting the travel of said carrier.

3. The combination, with the disk pivotally mounted and balanced on a center support, and having its center of gravity located below said support; of the traveling carrier movable in a circle above the surface of said disk and also movable in a vertical arc whose center coincides with the pivotal support of the disk; a weight adapted by contact with

and movement over the surface of the disk to deflect the disk and controlled by said carrier to travel in a circular path; an adjustable counterweight on said carrier; and means, as the stop-pins, for intermittently arresting the movement of said weight at intervals in its movement, as described.

4. The combination, with the power-shaft, of the sleeve fixed thereon; the rod fulcrumed on the lower end of said sleeve and movable in a vertical arc; a weight on one arm of said rod mounted to rotate thereon; an adjustable counterweight on the opposite arm; a disk

pivotaly mounted and balanced on a central pivot under said rod having its center of gravity located below said pivot; and the stop-pins standing in the path of the weight-carrying rod and adapted by their position to intermittently arrest the travel of said rod.

In testimony that I claim the foregoing I 20 have hereunto set my hand and seal.
